RECORD FILING DEVICE

Alexander Pafton Janssen, Charlottesville, Va., assignor to Acme Visible Records, Inc., Crozet, Va., a corporation of Delaware

Filed Sept. 28, 1964, Ser. No. 399,553

2 Claims. (Cl. 40—102)

This invention relates to improvements in record devices and particularly to new and improved hinges for swingably mounting flexible record panels on wire hangers, the wire hanger being adapted to be mounted on a holder in spaced parallel relation to a plurality of like hangers and endwise supported in the holder.

It is a particular object of the present invention to provide new and improved hinges which will facilitate the mounting of a plurality of flexible record devices on a single wire hanger, with tubular portions of the hinges which swingably mount the record panels on the hanger in abutting or substantially abutting engagement.

It has heretofore been proposed to employ record devices as aforesaid wherein the length of the tubular portion of the hinge which engages the wire hanger is of lesser length than the adjacent body portion of the hinge as in Hall United States Patent 2,690,781, or wherein the tubular portion of the hinge is of equal length to the adjacent main body portion of the hinge, such as in Hall United States Patents 2,498,808 and 2,537,268. In such instances where the side edges of the hinge body extends beyond or is flush with the ends of the tubular or barrel portion of the hinge, and where two or more record panels are mounted on a single wire hanger, there is created an excessive build-up of layers adjacent to the wire hanger, thus causing "fanning" of the record panels, i.e., an outward flaring instead of desired lying of the record panels in plane parallel relationship to each other. This is particularly accentuated when a plurality of wire hangers each carrying groups of record panels in hinged engagement thereon are mounted on a single holder.

It is an object of the present invention to prevent such fanning and to provide hinges constructed in a manner whereby when they are disposed adjacent to each other on a single wire hanger the record panels to which they are engaged will have space to flex, conform readily to a plane and thus lie flatter than was the case heretofore, and thus provide an overall more compact assembly.

The objects of the present invention are accomplished by constructing the hinges in a substantial T-shape; that is to say, with the length of the tubular portion greater than that of the adjacent flat main body portion of the hinge. This permits the tubular portions of the adjacent hinges to abut above the edges of the record panels while causing the adjacent body portions which lie against the record panel to be spaced from each other, thus permitting an area of flexing between adjacent hinge bodies on adjacent panels carried by the same wire hanger.

The objects and advantages of the present invention, its details of construction and arrangement of parts and advantages and economies thereof will be further apparent from a consideration of the following specification and accompanying drawings, wherein:

FIG. 1 is a longitudinal sectional view of a side elevation of a record holder device suitable for use in accordance with the present invention.

FIG. 2 is a fragmentary plan view of a pair of superimposed or adjacent record panels each having a hinge secured thereto with one in abutting relationship to the other in accordance with the practice of the present invention.

FIG. 3 is a section on the line 3—3 of FIG. 2.

FIG. 4 is a section on the line 4—4 of FIG. 2.

2

FIG. 5 is a perspective view of a plurality of hingedly mounted record panels on a single wire hanger in accordance with the practice of the present invention.

Referring to the drawings, the hinges of the present invention are composed of a strip of metal cut and bent to define a main body portion 10, a pair of legs or prongs 11, 11 extended through the record panel 12 and bent up into plane parallel relationship with the record panel 12 and the main hinge body 10. At the opposed end of the main hinge body 10, there is formed a barrel or tubular portion 13 adapted to receive a mounting wire hanger 14. The described hinge, insofar as it comprises the main body 10, prongs 11, and a tube or barrel portion 13, is substantially similar to the wire hanger shown in Hall Patent 2,690,781, with the exception that whereas in the aforesaid patent the main body portion extends beyond the tubular portion, in the present instance the tubular portion 13 extends beyond the side edges of the main body 10. In the aforesaid Hall Patents 2,498,808 and 2,537,268 the main body portion is of equal width or length with the tubular portion.

Although not shown, it will be understood that in the practice of the present invention the legs 11 can be shorter as in the case of the last two patents mentioned, and likewise the free edge of the tube 13 can terminate in a short flange extension in plane parallel relationship to the main body 10 as in the aforesaid last two patents when it is desired to engage the hinges to the record card by hand, rather than by machine.

The record body 12 can be composed of paper stock such as thin flexible paperboard, and instead of being a continuous flat sheet can be provided with a marginal edge portion defining a pocket therewith. In the alternate, the sheet material can be composed of flexible plastic and suitably in the form of a double sheet of plastic, providing a side edge open pocket, as shown in the illustrations of the present invention.

As appears from the relatively enlarged section of FIG. 3, wherein five record panels each of double thickness for mounting on a single wire hanger with the hinges of one record panel in substantially abutting relationship with the hinges of another panel, it will be seen that due to the spacing of the main body portions 10 of each adjacent hinge a flexing as at 15 is provided between the bodies in each adjacent hinge and thus inhibiting fanning out of the adjacent record panels and permitting a flatter, more compact, assembly. This of course is particularly important when a plurality of such wire hangers 14 are mounted in the holder device generally indicated as 16 with the hangers parallel and with their ends disposed in the notches 17 of the sides 18 of the holder body 16. In such case each group of record panels, while edgewise spaced from an adjacent group, largely overlies such group, and it is therefore especially important that each panel be as flat as possible.

Although I have shown and described a preferred embodiment of my invention, it will be understood by those skilled in the art that changes may be made in the details thereof without departing from its scope as comprehended by the following claims.

I claim:

1. A record device comprising a plurality of flexible record panels, a spaced pair of hinges swingingly mounting each of said record panels, and a wire hanger, said hinges each being of uniform contour and comprising a flat main body portion, prongs extending integrally and return bent from one edge of said body portion and lying in plane parallel spaced relation to one face of said body portion projecting through and in engagement with one edge portion of said record panels, and an integral tubular portion at the opposed end of said body lying

wholly on said one face and in engagement on said wire hanger and projecting over the engaged edge of the record panel, the length of said tube being greater than that of the adjacent flat main body portion of the hinge, the hinge tubes of one record panel being in substantial endwise abutment with the hinge tubes of an adjacent panel and freely pivotal with respect thereto.

2. A record device comprising a holder, a plurality of spaced parallel wire hangers endwise supported in said holder, a plurality of flexible record panels on at least one of said hangers, and a spaced pair of hinges swingingly mounting each of said record panels, said hinges each being of uniform contour and comprising a flat main body portion, prongs extending integrally and return bent from one edge of said body portion and lying in plane parallel spaced relation to one face of said body portion projecting through and in engagement with one edge portion of said record panels, and an integral tubular portion at the opposed end of said body lying wholly on said one face and in engagement on a wire hanger and projecting over the engaged edge of the record panel, the length of

5 said tube being greater than that of the adjacent flat main body portion of the hinge, the hinge tubes of one record panel of said plurality of panels mounted on a single hanger being in substantial endwise abutment with the hinge tubes of an adjacent panel and freely pivotal with respect thereto.
